Application August 22, 1935, Serial No. 37,275

6 Claims. (Cl. 122—94)

The present invention relates to a boiler structure particularly adapted for use on steam locomotives and has as its objective to provide a boiler of high steam generating capacity which at the same time is of relatively light weight.

Liquid or pulverized fuel is best adapted to provide for the high rates of combustion required to attain high steam generating capacity and the boiler described herein is especially suited for firing with pulverized fuel. As is well known, any material increases in combustion rates are usually accompanied by losses due to unburned carbon. These losses arise from improper gas mixture in the combustion space, localized segregation of combustible gases away from contact with oxygen due to lack of turbulence of the mass of gases or frequency because of an unimpeded stream line flow of gases from the fire box over the arch and through the fire tubes, lack of proper regenerative heat action, or because of combinations of these factors.

In the present boiler structure a combination of water tubes about the fire box and combustion chamber and fire tubes forwardly thereof provides ample heat absorbing surface together with gas areas sufficient to maintain draft requirements and enables the provision of the large effective combustion space that is desirable when burning pulverized fuel. An effective mixture of air and fuel is obtained by directing the fuel and secondary air entering the fire box in such manner as to cause turbulence of the gases and to avoid localized segregation of combustible gases or dead spots in the fire box.

The fire box is provided with a specially constructed arch arranged to preclude the usual rush of gases in stream line flow over the rear end of the arch to the fire tubes by causing them to flow through openings at the sides of the rear portion of the arch and laterally as well as forwardly thereof. This arrangement also retains the burning fuel within the fire box for a period sufficient to promote proper ignition and effective combustion. The walls of the fire box are lined with circulating tubes which adjacent the side openings of the arch are provided with refractory tile so that a maximum regenerative effect is obtained as the gases flow from the fire box through passages which have refractory covered surfaces.

To be suitable for locomotive use a boiler should possess the attribute which may be termed "flexible, self contained rigidity"; that is, it must be flexible enough to accommodate movements of the locomotive and provide for expansion or

contraction of its heated surfaces while at the same time be sufficiently rigid to withstand the shocks and strains encountered in use. The present boiler is constructed and supported so that its parts while rigidly interconnected are 5 flexibly carried on the locomotive frame.

The manner in which the above and other features and advantages are attained will best be understood upon consideration of the following detailed description of an illustrative embodiment of the invention as illustrated in the accompanying drawings in which:

Fig. 1 is a diagrammatic side elevational view of a locomotive boiler embodying the present invention; 15

Fig. 2 is a longitudinal sectional view through the fire box and combustion chamber of the locomotive;

Fig. 3 is an enlarged horizontal sectional view through the fire box on the line 3—3 in Fig. 2 20 and shows the improved arch of the invention;

Fig. 4 is a view of the rear head of the locomotive looking in the direction of the arrows in Fig. 2;

Fig. 5 is an enlarged sectional view through 25 the rear head of the locomotive taken along the line 5—5 in Fig. 4;

Fig. 6 is a vertical sectional view through the fire box along the line 6—6 in Fig. 2;

Fig. 7 is a vertical sectional view on the line 30 7—7 in Fig. 2;

Fig. 8 is an enlarged fragmentary sectional view on the line 8—8 in Fig. 6;

Fig. 9 is a fragmentary sectional view on the line 8—8 in Fig. 8 and illustrates the arch construction; 35

Fig. 10 is a view similar to Fig. 9 showing a modified arrangement of the arch construction;

Fig. 11 is an enlarged sectional view through the rear wall of the fire box on the line 11—11 40 in Fig. 5; and

Fig. 12 is a vertical sectional view on the line 12—12 in Fig. 2 and illustrates a sliding support for the boiler.

Referring to the drawings, the numeral 10 45 designates a steam and water drum disposed centrally above the fire box 12 and adjacent combustion chamber 13 of the locomotive. Drum 10 extends partly over a water barrel 14 and communicates with the upper central portion of the latter through several large nipples 15 (Figs. 2 and 7) suitably connected to the drum and barrel. The water barrel 14 is provided in usual manner with fire tubes and flues connected between the front and back sheets 16 and 17. Other 50 55

large nipples 18 connect the lower side portions of barrel 14 to a pair of water drums 20 disposed along and outwardly of the lower sides of combustion chamber 13 and fire box 12.

5 The side walls of the fire box and combustion chamber are lined with closely spaced riser tubes 21 connected at their lower ends into the drums 20 and at their upper ends into individual headers 22 (Figs. 2 and 6) which in turn are connected to the steam and water drum 10 by tubes 23 extending partially across the top of the fire box and combustion chamber. The use of individual headers provides for unequal expansion or contraction of these tubes due to varying 10 temperatures along the fire box and combustion chamber and also facilitates cleaning of these tubes.

A transversely extending header 24 connecting into drums 20 supplies water to arch tubes 30 20 extending rearwardly and upwardly in the fire box into the forward side of a header 31 open centrally of its upper side, at 32, to the water space in drum 10 and forming a downward extension of the latter. Header 24 also supplies 25 water to slag screen tubes 25 disposed above the central portion of the bottom of the fire box and connected at their rear ends into a transverse header 27 into which closely spaced tubes 28 lining the back wall of the fire box are also 30 connected. The upper ends of tubes 28 are staggered and alternate tubes connect into headers 49, 51, (Figs. 2 and 4) projecting from the sides of drum 10 and communicating therewith.

35 A series of small pipes 42, having their upper sides within the drum cut away, conduct steam from the drum 10 to dry pipes 43 which supply the inlet headers 44 for superheater tubes 46 located in combustion chamber 13. Headers 44 are disposed vertically outside the wall tubes 21 40 and the heat absorbing portions of the tubes 46 project into the combustion chamber between more widely spaced side wall tubes 21 and extend transversely of the chamber, the tubes that connect with headers at opposite sides of the 45 boiler being nested or intercalated longitudinally of the chamber 13, as shown in Fig. 3. The superheated steam headers 47 are also disposed vertically outside the wall tubes 21 and are connected to conduits 48 extending forwardly of the 50 sides of the locomotive to the throttle 50. The superheater is protected by a screen comprising staggered riser tubes 51 connecting at their lower ends into a transverse header 52 communicating with drums 20 and connected radially into drum 55 10 at their upper ends. A dry pipe 53 receiving steam from drum 10 through pipes 54, similar to pipes 42, supplies saturated steam to superheater elements 55 disposed within the flues of barrel 14, the superheated steam from elements 60 55 mixing with that from elements 46 and passing through throttle 50 and steam pipes 56 to the engines.

65 The forward end of the steam and water drum 10 is supported by the barrel 14 which is connected to transversely disposed flexible plates 68 (Fig. 2) secured to the locomotive frame 61. Further rearwardly below the forward end of the fire box 12 the drums 20 are provided with supporting members 63 slidable upon the underlying 70 portions of a transverse support 64 secured to the frame 61 and providing for longitudinal movement of the boiler relatively to the frame. The members 63 interlock with the transverse support 64, as indicated in Fig. 12, to prevent lateral 75 movement. Rearwardly of the back wall of fire

box 12 a transverse member 65 (Figs. 4 and 5) is connected to a flexible plate 66 secured to the locomotive frame. The outer ends of member 65 are formed to partially embrace and support the drums 20, also tying them together transversely 5 of the frame. Mounted on and secured to member 65 is a built-up saddle-like support 67 having its upper and lower portions formed to partially embrace the steam drum 10 and water drums 20, respectively, so that the steam drum 10 10 is rigidly supported at its rear end and tied to the water drums. The three drums, thus rigidly connected by the structure 65, 67, are flexibly connected and supported on the frame 61 by the member 66.

15 As may be seen in Figs. 3, 6, 8, and 9, the arch tubes 30 support refractory tile 33; the central portion 34 of the arch being completely covered from adjacent the forward end of fire box 12 to the back wall thereof, while the arch tubes along 20 the sides of the fire box are only partially covered so that at the rear portion of the arch lateral openings 35 are provided through which the flames may pass. In the constructions selected 25 for illustration herein the outermost row of refractory at each side covers the arch tubes from their forward ends to a point about midway of the fire box and in the adjacent row at each side the refractory extends further rearwardly but also terminates short of the back wall. Refractory tile 36 is also provided between these 30 circulating tubes 21 located along the side walls from adjacent the rear wall of the fire box to a point somewhat beyond the forward ends of the lateral passages through the arch. Thus, at this 35 portion of the fire box its side walls are lined with alternate vertical rows of exposed tubes 21 and refractory tiling 36. Protective tiles 37 are provided on the backs of the remaining tubes 21 along the side walls to the forward end of combustion chamber 13.

40 In the arch arrangement illustrated in Fig. 10 the outer arch tubes 39a are partially depressed below the level of the adjacent inner tubes 30b. Thus, the refractory tiles 34a supported between 45 these tubes are downwardly inclined and form ledge-like side extensions of the central part of the arch. The gases escaping from beneath the arch through the side openings 35 near the rear thereof flow around the ends of the refractory tile 50 34a and over the upper surfaces 34c thereof as indicated by the arrows, with resulting regenerative effect. Accordingly, this construction may be employed either in fire boxes having side wall tubes with or without refractory tile or in those 55 having a water leg side wall.

Secondary air for combustion is heated before 60 being admitted to fire box 12 centrally of the rear end thereof and adjacent the bottom thereof. As shown in Figs. 6 and 8, the outer side casing 70 is spaced from the plating 71 covering the insulation 72 on the backs of the tiles 36, 37 65 associated with the side wall tubes 21. Disposed between plating 71 and casing 70 is a corrugated sheet 73 serving not only as a reinforcement for the casing sheet 70 but also to divide the air space into a series of vertically extending channels 74. A similar corrugated sheet 75 lies in an air space formed above the tubes 23 connecting the headers 22 to drum 10. Air enters through 70 a longitudinally extending opening 76 (Fig. 6) along the top of the boiler at the sides of drum 10 and is caused to flow in parallel streams downwardly along the sides of the boiler through the 75 passages 74 on both sides of sheet 73 to be dis-

charged into the fire box through openings 77 in its side wall 78 near the bottom thereof.

Secondary air entering the combustion space is also heated as it passes to the central opening 80 in the rear inner wall of the fire box. As is shown in Figs. 4 and 5, air is admitted through openings 81 in the rear supporting member for drum 10 and passes between the outer casing plate 82 which is spaced from the insulation 83 lying outwardly of the refractory 84 associated with the rear wall tubes 28. Here also, parallel and vertical air passages 85 are formed by corrugations in a sheet 86. Air also enters through an opening 87 at the bottom of the rear wall of the fire box and flows upwardly toward the central opening 80 therein. The central portion of sheet 86 is dished to form a pocket 88 extending about the opening 80 in the rear wall. The air passages formed by the corrugations near the middle of sheet 86 discharge air, flowing both downwardly and upwardly toward the wall opening 80, into the pocket 88. Air from the upper and lower vertical passages at the sides of pocket 88 is conducted thereto by transverse ducts 89 formed by depressing the sheet 86 laterally at the sides of the pocket. In order to preserve the rigidity of sheet 86 the depressions made therein to form the ducts 89 are preferably of less depth than the pocket 88.

Located in the central wall opening 80 are a pair of telescoped sleeves 90 and 91 having flanges 92 by means of which they may be secured in place. The annular portions 93, 94 of the sleeves overlap and are spaced so that air from the surrounding pocket 88 flows around and between the sleeve portions 93 and 94 to pass about the periphery and through the aperture in a refractory annulus 95 disposed within sleeve 91 to enter fire box 12.

With the above described arrangements the secondary air for combustion purposes absorbs heat radiated to the refractory tiles and insulation associated with the side and rear wall tubes and thus efficiently utilizes what otherwise would be waste heat in order to preheat the secondary air and thus promote efficiency of combustion within the fire box.

Pulverized fuel is blown into the fire box by burners projecting through openings 96 (Fig. 4) near the lower corners of the support 67, platings 82, 87, etc. constituting the rear wall of the fire box. Fuel is projected upwardly toward a point forward of the central portion of the arch toward which secondary air entering through the wall opening 80 is also directed so that turbulence is created within the firebox to not only assure a proper mixture of air and fuel but also to eliminate dead spots in the fire box. Secondary air is also drawn in through the side openings 77. The gases flow forwardly and then rearwardly in the fire box as indicated by the arrows in Fig. 2 and inasmuch as escape of gases through the rear central part of the arch is precluded by the refractory thereon they must flow through the side openings 35. In escaping from the fire box the gases are in contact with the refractory 34, 36 on the arch and on the side walls, respectively, and thence flow, in part directly forwardly and in part laterally over the arch refractory and thence forwardly, to the combustion chamber so that the regenerative effect of the heated refractory assures complete combustion of the fuel.

The connection of steam and water drum 10 to barrel 14 and of the latter to the water drums 29 together with the provision of circulating tubes

21, 24, 30, 28, 51, connected between the drums 10, 20 and disposed in and about the fire box and combustion chamber provides for free and parallel circulation in the boiler and the scouring action of the gases on these tubes results in attaining a high generating rate. The boiler of the present invention is especially adapted for use upon the chassis of a certain modern and efficient type of locomotive and is calculated to obtain an increase of approximately thirty per cent in heat absorbed per square foot of surface and an increase of approximately fifteen per cent in the amount of fuel actually burned of that fired, as compared with the conventional fire tube boiler now utilized thereon. Notwithstanding this, the present boiler is also about fifteen per cent lighter than that now used. These increases in efficiency are due in large part to the fact that in burning pulverized fuel in the enlarged fire box and combustion chamber approximately eighty per cent of the work is done therein and also because the increased gas velocity makes substantially all of the heat absorbing surfaces more effective.

It is to be understood that there are many changes and variations which may be made in the details of construction of the boiler as described herein without departing from the invention and, therefore, it is desired and intended to include all such changes within the scope of the appended claims.

What I claim is:

1. In a locomotive type boiler; a fire tube barrel disposed forwardly of the combustion chamber; a steam and water drum positioned centrally above the fire box and combustion chamber extending forwardly above a portion of said barrel and communicating therewith; a pair of water drums disposed adjacent the lower sides of said fire box and combustion chamber and communicating with the lower side portions of said barrel; a header disposed transversely of the boiler adjacent the lower rearward end of the combustion chamber and connected with said water drums; a header disposed transversely below and communicating centrally thereof with the steam and water drum, said header being located above said first mentioned header; and arch tubes extending rearwardly and upwardly in the fire box and connected into said headers.

2. In a locomotive type boiler; a fire tube barrel disposed forwardly of the combustion chamber; a steam and water drum positioned centrally above the fire box and combustion chamber extending forwardly above a portion of said barrel and communicating therewith; a pair of water drums disposed adjacent the lower sides of said fire box and combustion chamber and communicating with the lower side portions of said barrel; a pair of headers connected with said water drums adjacent the rearward ends of the combustion chamber and fire box, respectively; circulating tubes connecting said headers and disposed above the bottom of the fire box; and circulating tubes located on the rear wall of the fire box and connecting the header at the rear portion of the latter with said steam and water drum.

3. In a locomotive type boiler; a fire tube barrel disposed forwardly of the combustion chamber; a steam and water drum positioned centrally above the fire box and combustion chamber and connected into the upper, rear, central portion of said barrel; a pair of water drums disposed adjacent the lower sides of said fire box

- and combustion chamber and communicating with the lower side portions of said barrel; a pair of headers connected with said water drums adjacent the lower rearward ends of the combustion chamber and fire box, respectively; circulating tubes connecting said headers and disposed above the bottom of the fire box; circulating tubes located on the rear wall of the fire box connected at their lower ends into the header at the rear portion of the fire box; and headers communicating with the steam and water drum and extending laterally therefrom and providing connections for the upper ends of the rear wall circulating tubes.
15. 4. In a locomotive type boiler having a fire box provided with arch tubes extending upwardly and rearwardly therethrough from the forward end to the rear wall thereof; refractory tile supported on the centrally located arch tubes from their forward ends to the rear wall of the fire box and on the outer side arch tubes from the forward end of the fire box to a point short of the rear wall thereof and forming lateral openings through the arch at the sides thereof adjacent the rear portions of the side walls of the fire box; and refractory disposed on the side walls of said fire box adjacent said lateral openings in the arch adapted to be contacted with regenerative effect by gases flowing from the fire box to said combustion chamber.
20. 5. In a locomotive type boiler having a fire box provided with arch tubes extending upwardly and rearwardly therethrough from the forward end to the rear wall thereof; refractory tile supported

on the centrally located arch tubes from their forward ends to the rear wall of the fire box and on the outer side arch tubes from the forward end of the fire box to a point short of the rear wall thereof and forming lateral openings through the arch at the sides thereof adjacent the rear portions of the side walls of the fire box; circulating tubes spaced along the side walls of said fire box; and refractory tile on said walls between said tubes adjacent said lateral openings in the arch adapted to be contacted with regenerative effect by gases flowing from the fire box to said combustion chamber.

6. In a locomotive type boiler having a fire box provided with arch tubes extending upwardly and rearwardly therethrough from the forward end to the rear wall thereof; refractory tile supported on the centrally located arch tubes from their forward ends to the rear wall of the fire box and on the outer side arch tubes from the forward end of the fire box to a point short of the rear wall thereof and forming lateral openings through the arch at the sides thereof adjacent the rear portions of the side walls of the fire box, an arch tube at each side of the fire box being depressed below the level of the adjacent inner arch tubes for at least that part of its length adjacent said openings whereby the refractory between said outer and inner tubes is inclined to form a refractory ledge contacted with regenerative effect by gases passing from the fire box to the combustion chamber.

VIRGINIUS Z. CARACRISTI.
